(57) **CLAIM**

The ornamental design for a display screen with animated graphical user interface, as shown and described.

DESCRIPTION

FIG. 1 illustrates a first image in a sequence for a display screen with animated graphical user interface (GUI) showing the new design;

FIG. 2 illustrates a second image thereof;

FIG. 3 illustrates a third image thereof;

FIG. 4 illustrates a fourth image thereof;

FIG. 5 illustrates a first image in a second sequence for a display screen with animated graphical user interface (GUI) showing the new design;

FIG. 6 illustrates a second image thereof;

FIG. 7 illustrates a third image thereof;

FIG. 8 illustrates a fourth image thereof;

FIG. 9 illustrates a first image in a third sequence for a display screen with animated graphical user interface (GUI) showing the new design;

FIG. 10 illustrates a second image thereof;

FIG. 11 illustrates a third image thereof;

FIG. 12 illustrates a fourth image thereof;

FIG. 13 illustrates a first image in a fourth sequence for a display screen or portion (GUI) showing the new design;

FIG. 14 illustrates a second image thereof;

FIG. 15 illustrates a third image thereof; and,

FIG. 16 illustrates a fourth image thereof.

In FIGS. 1–16, the dot-dash broken-line perimeter illustrates a display screen and forms no part of the claimed design.

The dashed broken lines outside this perimeter illustrate an
